UNITED STATES PATENT OFFICE.

THOMAS J. FEGLEY AND WALTER S. SNYDER, OF PHILADELPHIA, PENNSYLVANIA,
ASSIGNORS TO NORTH BRO'S. M'F'G. CO., OF PHILADELPHIA, PENNSYLVANIA, A
CORPORATION OF PENNSYLVANIA.

SCREW DRIVER.

1,415,822.

Specification of Letters Patent.

Patented May 9, 1922.

Application filed May 22, 1920. Serial No. 383,506.

To all whom it may concern:

Be it known that we, THOMAS J. FEGLEY and WALTER S. SNYDER, citizens of the United States, residing in Philadelphia, 5 Pennsylvania, have invented certain Improvements in Screw Drivers, of which the following is a specification.

Our invention relates to certain improvements in screw drivers of the "push" type 10 in which the screw driver is turned by pushing upon the handle and when the handle has been pushed to its full extent it engages the blade so that the blade can be turned on turning the handle.

One object of our invention is to improve 15 this type of screw driver by providing means for retracting the handle after it has been pushed forward.

A further object of the invention is to 20 provide means for connecting the handle with the blade, when the handle has been pushed in to its full extent.

These objects we attain in the following manner, reference being had to the accompanying drawings, in which,

Fig. 1 is a side view of our improved screw driver showing, in dotted lines, the handle directly connected to the spindle of the screw driver;

Fig. 2 is a longitudinal sectional view; showing the spring extended;

Fig. 3 is a detached sectional perspective view of the cylinder;

Fig. 4 is a perspective view of the bearing 30 collar;

Fig. 5 is a perspective view of the spindle;

Fig. 6 is a perspective view of the nut;

Fig. 7 is a perspective view of the coupling piece; and

Fig. 8 is a perspective view of the abutment ring.

1 is the cylinder having 2 internal spiral grooves in the present instance. 3 is the handle into which the upper end of the cylinder extends and to which it is attached in any suitable manner so that the cylinder will turn with the handle 3. 4 is a ferrule, which extends beyond the handle and rests 45 against the cylinder in the present instance.

The cylinder is preferably roughened, as shown in Fig. 1. 5 is a nut having threads, as illustrated in Fig. 6, which travel in the spiral grooves in the interior of the cyl-

inder. 6 is the spindle shaped at the lower end to engage the head of a screw. This spindle extends through the nut 5 and is reduced at its upper end 7 to form a rectangular extension which is adapted to a slot 8 in a coupling piece 9 carried by the handle. 55 This coupling piece has a head 10 which rests in a recess in the upper end of the cylinder, as shown in Fig. 2, and the head has a pin 11 adapted to slots 12 in the extreme end of the cylinder. The cylinder 60 has an internal thread 13 and adapted to this thread is an abutment ring 14. Between this ring and the head 10 of the coupling piece 9 is a spring 15 so as to allow the coupling piece to yield when the end 7 70 of the spindle 6 comes in contact with it and in the event of the spindle striking the end of the piece 9 it will be free to turn until it enters the slot 8, locking the spindle to the handle, as the spring 15 will drive the coupling piece forward and into engagement 75 with the spindle.

The nut 5 is slotted at 16 at its lower end and on the spindle is a pin 17, which projects into the slot so that the spindle must 80 turn with the nut. The nut has a certain amount of play on the spindle so that it can be engaged or disengaged therefrom. A pin 18 on the spindle above the nut limits the movement and also forms a support for 85 an abutment washer 19 and between this washer and the head 10 of the coupling piece 9 is a spiral spring 20 which returns the handle to its normal position as soon as it is released, so that the handle is always in 90 position to be pushed to turn the spindle. The spindle passes through a bearing collar 21 screwed into the lower end of the cylinder, as shown in Fig. 2.

The screw driver is used in the following 95 manner; where a screw is to be driven, the end of the spindle engages the screw and on pushing the handle forward the first movement causes the nut to engage the spindle and on the continued movement, the nut will 100 turn in the cylinder and turn the spindle, driving the screw to the depth required. When the spindle comes in contact with the coupling piece 8, the coupling piece will yield until the end of the spindle enters the 105 groove in the coupling piece, when the two will be locked so that on turning the handle the tool can be used as an ordinary screw

driver, since the coupling piece must turn with the handle. The moment the handle is released the spring 20 retracts the handle, returning it to its original position so that it will be in position to drive another screw.

We claim:

1. The combination in a push screw driver, of a spindle; a nut arranged to turn the handle; a cylinder having a spiral groove therein with which the threads of the nut engage; a spiral spring arranged to retract the handle after it has been pushed forward to turn the spindle; and a yielding coupling piece slotted to engage the spindle and connected to the handle so as to turn therewith.
2. The combination in a screw driver, of a spindle; a nut loose thereon and slotted at the lower end; a pin on the spindle with which the nut engages; a cylinder having two spiral grooves therein, the threads on the nut entering the grooves; a handle located on the upper end of the cylinder; a headed coupling piece mounted in the cylinder, the cylinder being slotted and the coupling piece having a pin entering the slot;

a spring back of the coupling piece, the coupling piece being recessed to receive the inner end of the spindle; and a coiled spring located between the spindle and the coupling piece.

3. The combination in a screw driver, of a spindle; a cylinder having two spiral grooves therein; a nut mounted on the spindle and having threads adapted to the grooves in the cylinder, the nut being notched at one end; the spindle having a pin adapted to the notch so that the spindle will turn with the nut; a pin on the spindle on the opposite side of the nut to limit the movement of the nut; an abutment washer supported by the pin; a headed coupling piece having a notch at its lower end to receive the upper end of the spindle so that the spindle will turn with the coupling piece; a spring back of the coupling piece; a handle enclosing the upper end of the cylinder; and a spring between the abutment washer on the spindle and the head of the coupling piece.

THOMAS J. FEGLEY.
WALTER S. SNYDER.
